UNITED STATES PATENT OFFICE.

JAMES M. DODGE, OF PHILADELPHIA, PENNSYLVANIA, ASSIGNOR TO THE
EWART MANUFACTURING COMPANY, OF CHICAGO, ILLINOIS.

CHAIN-WHEEL.

SPECIFICATION forming part of Letters Patent No. 366,819, dated July 19, 1887.

Application filed October 4, 1886. Serial No. 215,296. (No model.)

To all whom it may concern:

Be it known that I, JAMES M. DODGE, of Philadelphia, in the county of Philadelphia and State of Pennsylvania, have invented a new and useful Improvement in Chain-Wheels; and I do hereby declare that the following is a full, clear, and exact description thereof, reference being had to the accompanying drawings, making part of this application.

10 My invention relates to chain-wheels or sprocket-wheels, which are more especially adapted to and used for the purposes of idlers for supporting the horizontal runs of drive-chains of that type or species which is composed of centrally open links that lie (when the chain is in working condition) in planes alternately transverse to each other; and my invention consists in a novel construction of sprocket-wheel having alternately-arranged 15 single and duplex teeth constructed and operating as will be hereinafter more fully explained, and as will be more particularly defined and specifically pointed out in the claim of this specification.

20 To enable those skilled in the art to which my invention relates to make and use chain-wheels embracing my improvement, I will now proceed to more fully describe the latter, referring by letters of reference to the accompanying drawings, which form a part of this specification, and in which I have illustrated 25 my invention carried out in that form which is the best now known to me, and in which I have so far successfully practiced it.

30 In the drawings, Figure 1 is a side view or elevation of a sprocket-wheel made according to my invention, and showing in engagement therewith part of the wheel's rim of a drive-chain or carrier-chain such as my improved wheel is designed to be used in connection with. Fig. 2 is a cross-section of the chain-wheel, taken at the line $x-x$ of Fig. 1. Fig. 3 is a detail section at the line $y-y$, Fig. 2, showing one of the single teeth. Fig. 4 is 45 a similar section at the line $z-z$, showing one of the duplex or double teeth.

In the several figures the same part will be found designated by the same letters of reference.

50 A is the chain or sprocket wheel, and B

represents a section of drive-chain such as I contemplate using my improved wheels in connection with. This chain is composed of centrally open, oblong, or nearly rectilinear links, which are coupled together through the medium of cast saddle pieces or blocks, (according to United States Letters Patent granted to me on the 12th day of September, 1882,) and arranged alternately in planes transverse to each other; but of course any other construction or form of chain in which the links are centrally open and are arranged alternately in transverse planes may be used with equal advantage on my improved sprocket-wheel.

The wheel is composed, as shown, of a suitable hub like portion, c , arms d , and a rim, e , from which rim project outwardly and radially the teeth or sprockets f and g , which are of course equidistant circumferentially 70 of the wheel, but which are differently constructed, as will be presently explained, so that the single teeth g are adapted to enter or engage with the central openings of such ones of the chain-links as lie in a plane parallel to the axis of the wheel, while those marked f are double or duplex, and are adapted to straddle and hold or confine laterally those of the links which lie in a plane transverse to that of the axis of the wheel.

80 Each one of the teeth g is made preferably in skeleton form and somewhat after the pattern, in side view, of the teeth of a spur-gear, and of the proper size and shape to conveniently enter the open central space of the chain-links with which it is designed to engage, as clearly illustrated in the drawings, while the teeth f are in the form of two cheek-pieces, between which may be properly confined laterally those links of the chain which while 85 passing over the periphery of the wheel, lie in a plane transverse to the wheel's axis.

90 By reference to Fig. 1 it will be seen that the single teeth (marked g) will enter the central openings of some of the links of the chain, while those marked f will straddle and laterally confine certain other links of the chain, 95 while a reference to Fig. 2 will give a correct idea of the relative shape and arrangement of the single and double teeth projecting from 100

the rim *e* of the wheel, the duplex teeth or cheek-pieces *f* appearing at the upper part of the wheel in this sectional view, while the single teeth *g* are seen at the lower part of said figure. As the chain *B* travels in engagement with the wheel shown, the links of said chain are kept in mesh with the teeth of said wheel by reason of the successive engagement of the single teeth *g* with the horizontally-located links of the chain, and the laterally-engaging duplex teeth *f*, which straddle the vertically-arranged links of the chain and receive the draft-power by contact of their working-edges with the metallic blocks *i* of the chain.

It will be understood that when sprocket or chain wheels are used as idlers to support the horizontal runs of long and heavy drive or carrier chains of the type shown and described, it is necessary to have the teeth of the chain-wheel engage with each and every successive link of the chain, as otherwise any wobble of or tendency to twist in the chain is liable to throw the latter out of mesh or out of engagement with the teeth of the wheel, this result being especially liable where large or heavy chain is employed, and where the chain acts as a carrier, and has attached to it laterally-projecting flights or floats, which tend to make the chain tip or wobble about an axis coincident with its general line of draft. As the links of this kind of chain lie in alternately-arranged transverse planes, it is impossible to have the teeth of the sprocket-wheel as ordinarily constructed mesh or engage with more than every other one of the chain-links; but to overcome this difficulty I have devised and successfully employed the construction of wheel shown, in which every other tooth is adapted to engage with the central opening of a link, and every intermediate tooth or sprocket-like device is made duplex, so as to leave a seat or saddle-like receptacle between the teeth, on which the edge of a centrally-arranged link may rest, the edges or working-faces of the parts of such duplex sprocket working against either the end of one of the horizontally-arranged links or against any coupler device or connecting piece which may be arranged—as, for instance, shown at *i*—between the coupled ends of the central links.

A reference to Fig. 3 will show that the working or bearing surfaces of each single

tooth *g* are adapted to engage with the centrally-open links very much after the fashion of the ordinary sprocket or chain wheel tooth, 55 while an observation of Fig. 4 will make clear how the two-part or duplex teeth *f* are adapted to laterally embrace the links which lie in a plane vertical to the axis of the wheel, and how the rim portion of the wheel in between 60 the two parts of the duplex teeth *f* constitutes a sort of saddle or support for one edge of such vertically-arranged links.

Of course the details of construction may be varied more or less and the precise forms of 65 the parts modified without departing from the spirit of my invention so long as the principle of construction and mode of operation of the wheel shall be such that its alternate single teeth or sprockets will engage with the central 70 openings of every other chain-link and its alternate duplex teeth *f* will laterally embrace the links which lie in a plane transverse to the axis of motion of the wheel, substantially in the manner hereinbefore described, and so 75 that every link of the chain during the movement of the latter comes into engagement with some one of the sprockets of the chain-wheel.

Wishing it to be understood that I do not make any claim in this application to a chain-wheel formed or provided with apertures between the parts of the duplex teeth, as shown, 80 said construction forming the subject-matter of another application now pending by me, No. 215,297, what I claim herein as new, and desire to secure by Letters Patent, is—

A sprocket-wheel formed or provided with alternately-arranged single teeth and double teeth or saddle-like devices adapted, respectively, to engage with the central openings of 90 the drive-chain teeth, which lie in a plane parallel to the axis of the wheel's shaft, and to embrace the links which travel in a plane transverse to the axis of the wheel and come to bearings against the ends of the first-mentioned links, all substantially as hereinbefore 95 set forth.

In witness whereof I have hereunto set my hand.

JAMES M. DODGE.

In presence of—

D. S. GARWOOD,
C. A. FRY.
